G. R. VAN DER WEE.
BUNG AND FAUCET FOR BARRELS.

(Application filed Feb. 8, 1899.)

(No Model.)

UNITED STATES PATENT OFFICE.

GEORGE R. VAN DER WEE, OF ROCHESTER, NEW YORK.

BUNG AND FAUCET FOR BARRELS.

SPECIFICATION forming part of Letters Patent No. 712,108, dated October 28, 1902.

Application filed February 8, 1899. Serial No. 704,975. (No model.)

To all whom it may concern:

Be it known that I, GEORGE R. VAN DER WEE, a citizen of the United States, and a resident of Rochester, in the county of Monroe 5 and State of New York, have invented certain new and useful Improvements in Bungs and Faucets for Barrels, of which the following is a specification.

This invention relates to bungs and faucets 10 for barrels.

The object of the invention is to provide an effective device containing improvements over the devices of a similar kind heretofore known.

15 The invention consists in the devices and arrangements of parts hereinafter set forth.

In the drawings, Figure 1 is an elevation of a bung and faucet embodying my invention, a small portion being broken away in the 20 drawing to exhibit construction. Fig. 2 is a vertical section of the whole device on the line 2 2 of Fig. 1. Fig. 3 is an elevation of the main valve. Fig. 4 is a cross-section on the line 4 4 of Fig. 2. Fig. 5 is a plan view 25 of a detail of the device. Fig. 6 is a cross-section on the line 6 6 of Fig. 2. Fig. 7 is a top plan view of a bung when the detachable handled portion is removed, and Fig. 8 is a cross-section on the line 8 8 of Fig. 2.

30 In the drawings, A is a hollow casing provided with an external screw-thread a and forms the casing of the bung proper. The screw-threads are for engagement with the bung-hole of a barrel, and the casing is tapered on the portion where it is threaded in order the better to engage in bung-holes of 35 different sizes and to close the same tightly. In the figures the lower portion a' of the bung is reduced in size as compared with the screw-threaded portion, and at a suitable point of 40 this reduced portion a pin a^3 is screw-threaded into the wall of the reduced portion a' and extends into the interior of the casing. The lower portion of the casing, as shown in Fig. 45 2, is bored out cylindrically, and within it is a valve B. This valve has longitudinal ribs b , (see Figs. 3 and 6,) and the body of the valve is smaller than the interior area of the casing in which it moves, so that fluid may pass be- 50 tween the valve-body and the casing. The ribs b fit against the inner wall of the casing and serve to keep the valve B in position.

On the lower end of the valve B is a plate

B', which may be integral with the valve B or, as shown in the drawings, may be fastened thereto in any suitable way, such as by a screw b' . The plate B' has an upwardly-directed edge b^{10} , which may rest against a seat or packing a^{10} in the lower edge of the valve-casing. The upper end of the valve B is reduced in size to form a stem B^2 , which has a non-cylindrical cross-section in order that a key may be fitted upon it for the purpose of turning the valve B. In Figs. 3 and 4 the stem B^2 is shown flattened on two sides. 55 60 65

Upon a shoulder b^2 on the upper side of the valve-body B is a valve-face b^{20} , which may consist of a ring of hard or soft packing. This valve-face is adapted to fit against a valve-seat—that is, a ring C—that is screwed 70 into the casing A and has a downwardly-directed edge c , which is adapted to strike against the valve-face b^{20} , just mentioned. The ring is provided with means, such as the holes or sockets c' , for the engagement of a 75 suitable wrench inserted through the outward opening of the bung or casing A in order to adjust the position of the seat or ring with reference to the valve-face b^{20} .

In the side of the valve-body B is a slot, into 80 which the pin a^3 projects. This slot, as shown in Fig. 3, has two portions b^3 and b^{30} , running in parallel planes at right angles to the axis of the valve, and a diagonal portion b^{31} , connecting the two portions b^3 and b^{30} . It is obvious now that when the pin a^3 is in place if the valve-body B is turned it will not only have a rotary movement, but the fixed pin a^3 will cause longitudinal movement of the valve-body, which, if in the direction of the 90 arrow in Fig. 2, will move the valve from the position shown in said figure to a position permitting the passage of fluid past the valve edges b^{10} and c . The longitudinal movement is of course caused by the angular slot b^{31} . 95 When the pin a^3 is in one of the portions b^3 or b^{30} of the slot in the valve-body, pressure upon the valve-body B does not tend to move the valve from its position, as the slots b^3 and b^{30} are at right angles to the lines of longitudinal movement of the valve-body, and the valve is locked against movement by reason of pressure from gas or fluid in the barrel or in the pipe connections. 100

In the upper end of the casing A is a ring 105 A^4 , which is screwed into said casing and is

locked therein by any suitable means, such as the set-screw a^4 , Fig. 7, may be made in the ring A^4 for adjusting or for removing it. The inner edge of this 5 ring has two notches a^{10} , preferably set out of line with each other, as shown in Fig. 7. Through this ring passes the faucet-tube D, which is provided with a handle D^0 and is provided with means on its outer end for attachment 10 with a pipe for conducting away the contents of the barrel to which the bung is attached. In the drawings these means are indicated by the screw-threads d^0 . The lower end of the tube D is provided with a 15 valve-face d , which may be of hard or soft packing, and when the tube is in position in the bung this packing rests upon a valve-seat, the ring C, and forms a tight joint between the tube and said ring, and thus connects with 20 the interior of the barrel.

On the outside of the tube D is a shoulder d' , upon which rests a ring D' , having upon it lugs d^{40} out of line with each other and in positions suitable for passing through the 25 notches a^{10} in the ring A^4 . The ring D' is held against the shoulder d' by means of a locking-ring d^{10} , that is screwed upon the outside of the tube D and presses the ring against the shoulder d' , locking it in place. By means of 30 the ring d^{10} the position of the lugs d^{40} may be suitably adjusted with reference to the tube D and the notches a^{10} , so that when the tube D is removed from the bung or is inserted thereinto the proper engagement with the 35 stem B^2 may be made, for it is essential that the tube D should not be capable of removal from the bung A unless the position of the valve-body B closes the bung.

On the lower end of the tube D and inside 40 the bore thereof are a series of lugs or projections d^{20} , Fig. 4, which are adapted to engage the flattened sides of the stem B^2 of the valve B and leave channels around the stem B^2 , whereby fluid may pass through the tube D.

45 The device is complete as thus far described; but it is desirable to add a valve operating in the tube D when the tube is removed from the bung in order that fluid in the tube D may not flow backward therefrom 50 when it is separated from the bung. For this purpose I employ a back-pressure valve therein of the form now to be described.

At a suitable point in the tube D a ring d^{50} , forming a valve-seat, is set in the tube, and 55 a bar d^{60} , having a perforation d^{61} , extends across said tube at a suitable point, leaving passages on either side of the bar. The valve-stem moving in the perforation d^{61} guides the valve d^{51} directly to the valve-seat d^{50} , and

60 the stem d^{62} is of such length that when the tube D is in position in the bung and its valve-seat d engages against the ring C the valve d^{51} is pushed away from the seat d^{50} and the free passage of fluid is permitted.

65 In order to retain the valve d^{51} and its stem d^{62} in place in the tube D, the tube is bored out on the inside, so as to form a shoulder

d^{52} , and the valve d^{51} is provided with a series of arms d^{53} , which when the valve is moved outward (upward in Fig. 2) the ends of these 70 arms strike against the shoulder d^{52} and prevent the valve from being moved farther along the tube. In order to make this holding device, the arms d^{53} are made integral with the valve or are suitably fastened thereto. When the valve is inserted in the tube, the arms d^{53} are sprung inward toward the center of the valve, so as to be passed into the tube from the outer (upper) end, and when the valve is in place the ends of the 75 arms d^{53} are bent outward, so as to be adapted to engage against the shoulder d^{52} .

The operation of the device is as follows: The valve B is supposed to be in the position shown in Fig. 2, with the valve edges c and b^{10} 80 pressing against their packings b^{20} and a^{10} , respectively, closing the inlet into the bung. In this position the pin a^3 is in the portion b^3 of the slot in the valve B. If now the faucet (which comprises the tube D and its appurtenances) is inserted through the ring A^4 , the lugs d^{40} pass through the notches a^{10} until the valve-seat d presses tightly against the upper side or edge of the ring C. When the parts are in this position, the faucet can be 95 turned with reference to the casing A, thus bringing the lugs d^{40} under solid portions of the ring A^4 and locking the parts firmly in place. The lugs d^{40} may be slightly beveled in order to engage easily with the under side 100 of the ring A^4 and in order to press the end of the tube more solidly upon its seat. The bevels may of course be made on the ring A^4 , or both the lugs and the ring may be beveled for this purpose. When the tube or faucet D is inserted through the ring A^4 , it fits upon the stem B^2 105 of the valve B, but without turning it, and when the tube D is turned the lugs d^{40} are brought under the ring A^4 , locking the bung and tube together, and at the same time the valve B turns with the tube and causes the pin a^3 to act along and through the diagonal portion b^{31} of the slot and until the pin rests in the straight portion b^{30} , thus not only rotating the valve B, but causing it to move 110 longitudinally in the direction of the arrow in Fig. 2, and thus opens a free outlet through the bung and through the tube D. The ends of the slots b^3 and b^{30} of course limit the extent of rotation of the bung, and therefore 115 of the faucet D. The longitudinal movement of the plate B' away from the end of the bung-casing breaks away any adhering pitch or other substance employed for lining the barrel, and the rotary movement of the plate as- 120 sists in this function.

The construction shown permits easy and accurate adjustment and repair of each of the valves in the casing A and access thereto from the outer end of the casing.

What I claim is—

1. In a combined bung and faucet, the combination of a bung-casing, a longitudinally-movable valve therein, an adjustable seat

for said valve within said casing, an insertible tubular faucet adapted to engage said valve for operating the same and to make contact with the end of said faucet against 5 said valve-seat, and means, adjustable independently of said valve-seat, for locking said faucet in said bung-casing.

2. In a combined bung and faucet, the combination of a bung-casing, a longitudinally-movable valve therein, an adjustable seat for 10 said valve within said casing, an insertible tubular faucet adapted to engage said valve for operating the same and to make contact with the end of said faucet against said valve-seat, an adjustable ring in the outer end of 15 said bung-casing, and a device upon said faucet for engaging said ring for locking said faucet in place and for pressing its end against said seat.

20 3. In a combined bung and faucet, the combination of a bung-casing, a longitudinally-movable valve therein, an adjustable seat for said valve within said casing, an insertible tubular faucet adapted to engage said valve 25 for operating the same and to make contact with the end of said faucet against said valve-seat, an adjustable ring in the outer end of said bung-casing having notches on the inner side thereof, and an adjustable device upon 30 said faucet having lugs for passing through said notches and for engaging said ring for locking said faucet in place and for pressing its end against its seat.

4. In a combined bung and faucet, the combination of a bung-casing, a rotating and longitudinally-movable valve therein, provided 35 with an outwardly-projecting stem; means for causing said valve to move longitudinally when rotated, an adjustable valve-seat for 40 said valve within said casing, an insertible tubular faucet adapted to engage said stem for operating said valve and to be seated against said valve-seat, an adjustable ring in the outer end of said casing through which 45 the faucet passes, and means upon said faucet for engaging said ring for locking the faucet in place and for pressing its end against said valve-seat.

5. In a combined bung and faucet, the combination of a bung-casing, a rotating and longitudinally-movable valve therein provided 50 with an outwardly-projecting stem, means for causing said valve to move longitudinally when rotated, an adjustable valve-seat for 55 said valve within said casing, an insertible tubular faucet adapted to engage said stem for operating said valve and to be seated against said valve-seat, an adjustable ring in the outer end of said casing through which 60 the faucet passes, and a device upon said faucet for engaging said ring for locking said faucet in place and for pressing its end against its seat.

6. In a combined bung and faucet, the combination of a bung-casing, a rotating and longitudinally-movable valve therein provided 65 with an outwardly-projecting stem, means for

causing said valve to move longitudinally when rotated, an adjustable valve-seat for 70 said valve within said casing, an insertible tubular faucet adapted to engage said stem for operating said valve and to be seated against said seat, an adjustable ring in the outer end of said bung-casing having notches on the inner side thereof, and an adjustable 75 device upon said faucet having lugs for passing through said notches and for engaging the under side of said ring for locking said faucet in place and for pressing its end against its seat.

80 7. In a combined bung and faucet, the combination of a bung-casing, a valve therein, an insertible tubular faucet adapted to engage said valve for operating the same, means for locking said faucet in place in said bung-casing, and a back-pressure valve in the faucet 85 that is opened by setting the faucet in place in the casing.

8. In a combined bung and faucet, the combination of a bung-casing, a valve therein, an insertible tubular faucet adapted to engage 90 said valve for operating the same, means for locking said faucet in place in said bung-casing, and a back-pressure valve in the faucet 95 having a stem adapted to engage the first-mentioned valve when the faucet is adjusted in the bung-casing whereby said back-pressure valve is held open while the faucet is in place.

9. In a combined bung and faucet, the combination of a bung-casing, a valve therein 100 provided with an outwardly-projecting stem, an insertible tubular faucet adapted to inclose said stem for operating said valve, means for locking said faucet in place in said 105 bung-casing, and a back-pressure valve in the faucet having a stem adapted to engage said stem when the faucet is adjusted in the bung-casing whereby said back-pressure valve is held open while the faucet is in place. 110

10. In a combined bung and faucet, the combination of a bung-casing, a valve therein, an insertible tubular faucet adapted to engage 115 said valve directly by its stem for operating the valve, means for locking said faucet in place in said bung-casing, and a back-pressure valve in the faucet that is opened by setting the faucet in place in the casing.

11. In a combined bung and faucet, the combination of a bung-casing, a valve therein, an 120 insertible tubular faucet adapted to engage said valve directly by its stem for operating the valve, means for locking said faucet in place in said bung-casing, and a back-pressure valve in the faucet having a stem adapted to 125 engage the first-mentioned valve when the faucet is adjusted in the bung-casing, whereby said back-pressure valve is held open while the faucet is in place.

GEORGE R. VAN DER WEE.
